WILLIAM B. GREENE, OF EAST CLEVELAND, OHIO, ASSIGNOR TO THE ADAPTI MANUFACTURING COMPANY, OF CLEVELAND, OHIO, A CORPORATION OF OHIO.

DISTRIBUTING-BOX.

1,121,850.

Specification of Letters Patent.

Patented Dec. 15, 1914.

Application filed March 6, 1914. Serial No. 822,961.

To all whom it may concern:

Be it known that I, WILLIAM B. GREENE, a citizen of the United States, residing at East Cleveland, in the county of Cuyahoga and State of Ohio, have invented a certain new and useful Improvement in Distributing-Boxes, of which the following is a full, clear, and exact description, reference being had to the accompanying drawings.

This invention relates to improvements in the class of distributing boxes for electric conduits, that are composed of a body portion to which may be applied interchangeable side plates or members of varying design and purpose, whereby the distributing box may be made adaptable to practically any situation arising in the work wherein the box is employed.

The objects of my invention are to provide a box of the above character which is very rigid and substantial; yet simple of construction and economical of production; the rigidity of the box resulting from the comparatively large bearing surfaces that are provided for the side plates or members, and the very efficient securing means therefor.

The above and further objects, which will become apparent as this description proceeds, are attained by a construction illustrated in the accompanying drawing, wherefore—

Figure 1 is a perspective of the body portion of my improved distributing box; Figs. 2, 3, and 4 illustrate various forms of side plates or members which may be applied to the body portion shown in Fig. 1; Fig. 5 is a bottom plan view of the box the cover being omitted and a portion of the box being broken away to more clearly show its construction, said figure also showing one of the side plates or members partially removed from the box; and Fig. 6 is a section on line 6—6 of Fig. 5; the box, in said figure, being provided with a cover.

The body portion of the box comprises a circular plate 1 having an annular ledge 2 that is spaced a slight distance from the edge of the plate, and from which projects, at equal distances therearound, posts 3; said posts being disposed at substantially right angles to the plate 1. As will be clearly seen from the drawing, the posts 3 are, in effect, continuous extensions of the ledge 2 and the outer surfaces of the posts and the ledge are

coincident. Each of the posts 3 carries, at about its longitudinal center, a large headed screw 4 which is threaded through the post and is radial with respect to the circular plate 1. This arrangement causes the screws, in adjacent posts, to diverge or separate as they are unscrewed, a feature which is of considerable importance as a matter of convenience and of economy of time, as will be appreciated as this description proceeds. 65

As I have mentioned hereinbefore, side plates of various kinds and having different functions, may be applied to the body portion of my distributing box, for the purpose of making the box adaptable to different situations; and the simplest form of these side plates, or the one which I will refer to as the blank side plate, is shown particularly in Fig. 2 and designated 5. This plate is preferably made of sheet metal and is curved to conform to the edge of the plate 1, is of a width corresponding to the height of the posts 3, and is of a length approximately equal to the distance between the centers of adjacent screws 4, the plate being 70 notched at 6 for the accommodation of said screws.

In Fig. 3 I have shown a side plate or member which has a base 7 that corresponds in size and shape to the plate 5, the same 85 having screw receiving notches 7^a and which is provided with a hollow, internally threaded boss 8 for the reception of the threaded end of an electric conduit. This form of side plate or member I will refer to hereinafter as a conduit fitting. Usually a distributing box will consist of a body portion having applied to it two or more conduit fittings, the box being completed by the insertion of the required number of blank side 90 plates, the conduit fittings being arranged opposite each other as shown in Figs. 5 and 6, or placed at an angle with respect to each other, as the nature of the work requires. However, it is frequently desirable to include in the box an insulating side plate 95 which is shown in Fig. 4, the plate having openings through which wires may be led, said wires, thereafter, being supported upon cleats if desired. This plate is composed, as 100 the name implies, of insulating material, such as fiber or other similar composition. The insulating plate, which is designated 9 in the drawing, is of substantially the same shape as the plate 5, and it is thickened at 110

10 for the purpose of strengthening the plate and has a series of openings 11 through which wires may pass. A comparatively large bearing surface is provided for the side members, the posts 3 forming bearings for the ends of said members and the ledge 2 forming an abutment for one of the side edges thereof. Now, because of the divergence of the screws 4, the members may 15 be applied to, and removed from the box without the entire removal of the screws 4 from the posts 3; and because the screws are contained within the notches formed in the ends of the members, they act as keys 20 to retain the members against lateral movement. When the screws are tightly "set up" against the members, the enlarged heads of the screws will overlie and engage adjacent ends of consecutive members and 25 very effectively hold them against displacement. A cover 12 is provided for the box and consists of a circular plate of approximately the same size as the base 1 and is secured to the lower ends of the posts 3 by screws 13 that are threaded into the ends 30 of said posts.

From the foregoing description it will be seen that my invention provides a very substantial and rigid distributing box, the 35 rigidity being assured through the comparatively large bearing surfaces provided for the side plates or members, and the central location of the screws 4 with respect to the longitudinal dimension of the posts 3; and that, furthermore, the side plates or 40 members are not only interchangeable, but are invertible because of their being symmetrical in outline; both of which features add materially to the desirability of the 45 box, and the ease with which it may be assembled.

Having thus described my invention, I claim:

1. In a distributing box, the combination, 45 with a body portion comprising a plate having a plurality of posts which project at substantially right angles therefrom, of side members having their ends resting upon adjacent posts, and a screw threaded into 50 each post and having a head that overlies and engages adjacent ends of consecutive side members, the screws diverging outwardly from the posts.

2. In a distributing box, the combination, 55 with a body portion comprising a plate having a plurality of posts which project at substantially right angles therefrom, of side members having their ends resting upon adjacent posts, the length of the posts and 60 the width of the side members being substantially equal, and a screw threaded into each post and having a head that overlies and engages the adjacent ends of consecutive side members, the screws diverging 65 outwardly from the posts and located at

substantially the longitudinal centers thereof, as and for the purpose specified.

3. In a distributing box, the combination with a body portion comprising a plate having a plurality of posts which project at 70 substantially right angles therefrom and a ledge extending between the posts and having its outer surface substantially coincident with the corresponding surfaces of the posts, of side members which have their ends resting upon the posts and one of their side edges in engagement with the aforesaid ledge, and a screw threaded into each post and having a head that overlies and engages the adjacent ends of consecutive side members. 75

4. In a distributing box, the combination, with a body portion comprising a plate having a plurality of posts which project at substantially right angles therefrom and 80 a ledge extending between the posts and having its outer surface substantially coincident with the corresponding surfaces of the posts, of side members which have their ends resting upon the posts and one of their side edges in engagement with the aforesaid ledge, the width of the side members and the length of the posts being substantially equal and a screw threaded into each post 85 at about its longitudinal center and having a head that overlies and engages the adjacent ends of consecutive side members, the 90 ends of the side members having screw receiving notches.

5. In a distributing box, the combination, 100 with a body portion which comprises a circular plate having an annular ledge that is spaced from the edge thereof and a plurality of posts projecting from said ledge at substantially right angles to the plate, of 105 side members having their ends resting upon adjacent posts and one of their side edges engaging a portion of said ledge, the width of the side members and the length of the posts being substantially equal, and a screw 110 threaded into each post and extending therefrom in a direction that is radial with respect to the aforesaid plate, the screw having a head that overlies and engages adjacent ends of consecutive side members, the 115 screws being located at substantially the longitudinal center of the posts, and the ends of the side members being provided with screw receiving notches.

6. In a distributing box, the combination, 120 with a body portion comprising a plate and a plurality of posts which project at substantially right angles therefrom, of side members having their ends resting upon adjacent posts, the width of said side members 125 and the length of the posts being substantially equal, a screw threaded into each post and located at substantially the longitudinal center thereof and having a head that overlies and engages adjacent ends of con- 130

secutive side members, a cover for said box, and means whereby the cover may be secured to the ends of the aforesaid posts.

7. In a distributing box, the combination, 5 with a body portion comprising a plate having a ledge which is spaced from the edge thereof and a plurality of posts which project from said ledge at substantially right angles to the plate, of side members having 10 their ends resting upon the posts and one of their side edges engaging a portion of the aforesaid ledge, a screw that is threaded into each post and is located at substantially

the longitudinal center thereof and having a head that overlies and engages adjacent 15 ends of consecutive side members, the ends of said side members having screw receiving notches, a cover for said box, and means whereby the cover may be secured to the ends of the posts.

In testimony whereof, I hereunto affix my signature in the presence of two witnesses.

WILLIAM B. GREENE.
